US00D885903S

(12) **United States Design Patent** (10) Patent No.: **US D885,903 S**
(45) Date of Patent: **** Jun. 2, 2020**

(54) **LID**

(71) Applicant: **YETI Coolers, LLC**, Austin, TX (US)

(72) Inventors: **Mark Carlson Rane**, Austin, TX (US);
Elizaveta Morris, Austin, TX (US)

(73) Assignee: **YETI Coolers, LLC**, Austin, TX (US)

(**) Term: **15 Years**

(21) Appl. No.: **29/643,732**

(22) Filed: **Apr. 11, 2018**

(51) LOC (12) Cl. **09-07**

(52) U.S. Cl.

USPC **D9/453**

(58) **Field of Classification Search**

USPC ..... D3/202, 203.1, 203.2, 318; D7/300, D7/300.1, 316, 317, 323, 354, 387, 391, D7/392, 392.1, 396.1, 396.2, 397, 398, D7/503, 509, 510, 511, 523, 526-531, D7/538, 566, 568, 600.1, 602, 603, 614, D7/619.1, 629, 704, 900; D9/434, 435, D9/440, 447, 452, 453, 499, 516, 529, D9/686, 723; D23/259, 260, 261; D24/121, 127, 199, 224; D34/7, 10, 11 CPC B65D 2517/5091; B65D 41/04; B65D 23/12; B65D 1/0246; B65D 47/265; B65D 51/24; B65D 51/224; B65D 51/245; B65D 2101/0015; B65D 2251/0093; B65D 85/72; B65D 51/18; B65D 51/28; B65D 51/242; B65D 51/2814; B65D 51/2821; B65D 21/0228; B65D 41/3447; B65D 1/02; B65D 50/041; B65D 2215/02; A61L 9/12; A47G 19/2205; A47G 19/2222; A47G 19/2266; A47G 19/2272; A47G 19/2294; A47G 19/22; A47J 43/27; B05B 7/2437; B05C 17/00576; E03F 5/02; A01M 1/02; A01M 1/04; A01M 1/106

(57) **CLAIM**

The ornamental design for a lid, as shown and described.

DESCRIPTION

FIG. 1 is a top, front, left perspective view of a lid showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a cross-sectional view taken in the direction of line 8-8 from FIG. 2 thereof.

The broken lines are shown for the purpose of illustrating parts of the article that form no part of the claim.

1 Claim, 6 Drawing Sheets
